UNITED STATES PATENT OFFICE.

CARL FRIEDRICH TELLER, OF OFFENBACH-ON-THE-MAIN, GERMANY,
ASSIGNOR TO THEODOR MAYNZ, OF SAME PLACE.

LETTER-BOX.

SPECIFICATION forming part of Letters Patent No. 358,632, dated March 1, 1887.

Application filed October 26, 1886. Serial No. 217,207. (No model.) Patented in Germany December 24, 1885, No. 35,873; in France December 31, 1885, No. 160,630, and in Austria-Hungary February 4, 1886, No. 5,818 and No. 24,188.

To all whom it may concern:

Be it known that I, CARL FRIEDRICH TELLER, of Offenbach-on-the-Main, in the Empire of Germany, have invented new and useful 5 Improvements in Letter-Boxes, (which have been patented in Germany December 24, 1885, No. 35,873; in France December 31, 1885, No. 160,630, and in Austria-Hungary February 4, 1886, No. 5,818 and No. 24,188,) of which 10 the following is a specification.

The object of my invention is to provide a new and improved letter-box which permits of being emptied of its contents without the letters being handled by the operator.

15 The invention consists of a letter-box and a letter bag or pouch which are dependent upon one another, so that one cannot be opened or closed without the other.

The invention also consists of various parts 20 and details and combinations of the same, as will be fully described hereinafter, and then pointed out in the claims.

Reference is to be had to the accompanying drawings, forming a part of this specification, 25 in which similar letters of reference indicate corresponding parts in all the figures.

Figure 1 is a perspective view of my improved letter-box. Fig. 2 is a front elevation of the letter-bag in position on the bottom of the letter-box. Fig. 3 is a side elevation of the same, showing the letter-bag closed and in position on the bottom of the letter-box. Fig. 4 is a similar view showing the letter-bag open on the bottom of the box. Fig. 5 is a plan 30 view of the bottom of the letter-box. Fig. 6 is an under-side view of the bottom of the letter-box. Fig. 7 is a sectional side elevation on the line xx of Fig. 1. Fig. 8 is a front elevation of the inside of one of the bow-frames 35 of the letter-bag. Fig. 9 is a plan view of the same. Fig. 10 is a front elevation of the same, showing the bolts in a closed position. Fig. 11 is a plan view of the letter-bag in a closed 40 position. Fig. 12 is a sectional side elevation of one of the bow-frames on the line yy of Fig. 11. Fig. 13 is a similar view of the same, showing the unlocking of the bolt. Fig. 14 is a sectional end elevation of the same on the line zz of Fig. 12. Fig. 15 is a side elevation 45

of the rear part of the bottom of the letter-box with the bag in a closed position. Fig. 16 is a similar view of the same with the letter-bag in an open position. Fig. 17 is a plan view of one corner of the bottom of the letter-box. Fig. 18 is a sectional front elevation 50 on the line vv of Fig. 17, showing the drop-bottom unlocked; and Fig. 19 is a similar view showing the drop-bottom in a locked position.

The letter-box A, of suitable construction 55 and form, is provided with a bottom, B, consisting of the frame D and the drop-bottom E, hinged near the front end part, E', to the under side of the said frame D and opening downward. The sliding spring-bolts F are 60 arranged on the under side of the said frame D, and project a short distance inward under the drop-bottom E, and hold the same in a closed position.

Each of the bolts F is inaccessible from the 65 exterior of the box A by being inclosed in a casing made in two parts, D' and E', of which the part D' is secured to the bottom of the frame D, and the other part, E', is attached to the drop-bottom E, as shown in Figs. 18 and 19. 70

The under side of the frame D is provided 75 on each side with a guide-bar, G, carrying a guide-bolt, H, having a wedge-shaped front, H², which engages, when pushed forward, with the downwardly-extending arm F' of the 80 sliding bolt F, so as to cause the latter to move sidewise and outward until the inner end of the bolt F disengages the drop-bottom E and permits the latter to swing downward. When the wedge-shaped end H² of the bolt 85 H disengages the said bolt F, then the latter is again forced to its former position by its coiled spring. This movement of the guide-bolt H is effected by a device arranged in connection with the letter-bag I, which consists, 90 principally, of the usual bag-part, I', fastened to two bow-frames J and K, hinged together at I'.

Each of the bow-frames J and K is provided 95 on each end with the projecting lugs L and L', respectively, by means of which the letter-bag I can be supported on the guide-bars G and moved on the latter to the rear

end of the letter-box A. On the inside of the bow-frame J is arranged a lock, M, provided with the bolts O and O', each having on its inner end rack-teeth O², which engage a pinion, P, mounted upon a shaft, P', having a square end, which projects beyond the plate, covering the said racks and pinion. The outer round ends of the said bolts O and O' project through the ends of the bow-frame J, and each 10 is provided with a key-bit, O³, on the extreme outer end, which bit, in its normal position, is held in a correspondingly-shaped aperture formed in the projection L. Each of the bolts O and O' is also provided with a hook, O', 15 which engages, when the bow-frames J and K are closed, with similar hooks, K', formed on the inside of the bow-frame K. The bolt O has a notch, O⁵, which engages, when the bolt is closed or in its innermost position, with a 20 catch, Q', formed on the spring Q, secured to the said frame J.

On the bow-frame K is arranged a key, R, which is capable of being turned, but is otherwise fixed on the frame, and fits, when the bag 25 is closed, upon the square end of the shaft P', so that when the said key R is turned it imparts a sliding motion to the bolts O and O' by means of the pinion P after the spring Q is disengaged from the bolt O. In one corner of 30 the bow-frame K is arranged a flat spring, T, which engages, by its upper projecting end, T', (see Figs. 12, 13, and 14,) when the bag I is closed, with the inclined catch end Q' of the spring Q. The lug L' in this corner of the 35 frame K is provided with a key-hole, in which fits a key, U, which, when pressed inward, causes the spring T to move in the same direction, which raises the inclined catch end Q' of the spring Q, so that the latter is raised and 40 disengages the notch O⁵ in the bolt O. Without this key U it is impossible to open the bag I, and as this key is deposited in the post-office in which the bag is to be emptied it is evident that the letter-collector is prevented from opening the bag when carrying the same.

In the rear end and on the under side of the box A is arranged a knob, V, which has the inwardly-extending shank V', held in a casing, V², and having a coiled spring, V³, which holds 50 the said shank V' and its knob V in a normal position, and prevents an inward movement of the same. The inner end of the shank V' corresponds to the key U.

The bow-frame K is provided with lugs K², 55 which serve to raise the drop-bottom E, and are also used for fastening shoulder-straps, by which the bag I can be carried.

The emptying of the letter-box A takes place in the following manner: After the closed 60 and locked letter-bag I has been placed, by means of its lugs L and L', upon the guide-bars G on the letter-box A, then the bag I is moved inward against the rear wall of the box A, so that the outer ends, O³, of the bolts O and O' 65 are opposite corresponding apertures in the guide-bars G, and the key held in the lug L' of the bow-frame K is opposite a correspond-

ing aperture in one of the guides G, the said aperture being opposite the shank V' of the knob V. The operator now presses on the 70 knob V, and thereby disengages the catch Q' of the spring Q from the sliding bolt O, and at the same time the operator turns the key R on the bow-frame K, whereby the bolts O and O' are moved outward and the hooks O' and K' 75 are disengaged, thus permitting of opening the bag I. This is done by pulling the bow-frame K toward the front, as shown in Fig. 4. The forward movement of the bow-frame K causes a turning motion of the bow-frame J, so that 80 the bits O³ of the bolts O and O' act on the recesses H' of the sliding bolts H, and cause a forward movement of the latter in the direction of the arrow a', (see Figs. 15 and 16,) whereby the wedge-shaped end H² of the bolt 85 H presses against the arm F' of the bolt F, and causes the latter to slide outward, so that the drop-bottom E is disengaged and swings downward into the open bag I, as indicated in dotted lines in Fig. 4. The contents of the 90 box A are thus dropped into the said bag. It will be seen that the bow-frame J is held in a firm position in the rear of the box A, on account of the outer ends of the bolts O and O' passing through the corresponding apertures 95 in the guides G, thus forming a fulcrum for the bow-frame J to swing on. After the contents have been emptied into the bag I, then the operator again pushes the bow-frame K toward the rear, whereby the drop-bottom E 100 is raised to its former position by the lugs K², and the frame J swings downward again and causes, by means of the bits O³ of the bolts O and O', a backward motion of the sliding bolts H, which thus release the bolts F, which are 105 forced inward and under the drop-bottom E by flat springs, thus locking the drop-bottom again in position. By turning the key U in the proper direction it causes the bolts O and O' to move inward, so that the hooks O' of the 110 bow-frame J again engage the hooks K' of the bow-frame K, whereby the bag is locked and the spring-catch Q' again engages the notch O⁵ of the bolt O, and the pressure of the knob V is released. The letter-bag can now be withdrawn from the box A. 115

Having thus described my invention, what I claim as new, and desire to secure by Letters Patent, is—

1. A letter-box provided with the knob V 120 and the spring-key shank V', by which the letter-bag pushed under the box can be opened, substantially as shown and described.

2. The combination, with the drop-bottom E, of the frame D, on which the said bottom is hinged, the spring-bolts F, holding the said bottom closed, and means for withdrawing the said spring-bolts, substantially as shown and described. 125

3. The combination, with a letter-box provided with the guide-bars G, of the letter-bag I, provided with the bow-frames K and J, of which the frame J is provided with a lock the bolts of which engage apertures in the said 130

guide-bars of the letter-box and establish a connection between the bag and the letter-box, substantially as shown and described.

4. A letter-box provided with the guide-bars G and a knob, V, carrying the spring-key shank V', in combination with the letter-bag I, provided with the bow-frames J and K, having the lugs L and L', the lock M on the bow-frame J, having the bolts O and O', engaging apertures in the said guide-bars, and the key R, for operating the said lock M, substantially as shown and described.

5. A letter-box provided with the bottom B, consisting of the frame D, carrying the guide-bars G, and the hinged drop-bottom E, the spring-bolts F, arranged on the said frame D, and the sliding bolts H, operating on the said spring-bolts F, in combination with the bow-frames J and K, and the lock M on the bow-frame J, provided with the bolts O and O', operating with their outer bit ends, O³, the said sliding bolts H, substantially as shown and described.

6. A letter-box provided with the bottom B, consisting of the frame E, carrying the guide-bars G, the drop-bottom E, hinged on the said frame D, the sliding bolts F, arranged on the said frame D, and the knob V, having a spring-key shank, V', in combination with the bow-frames J and K, the lock M on the bow-frame J, provided with the bolts O and O', engaging with their outer bit ends, O³, the said sliding bolts H, the key R on the bow-frame K, the

spring T, secured to the bow-frame K and operated by the spring-key shank V' and the knob V, and the spring Q, engaging the notch O⁵ in the said bolt O' and operated by the said spring T, substantially as shown and described. 35

7. The knob V, arranged on the outside of the letter-box and provided with the spring-key shank V', in combination with the bow-frames J and K, the spring T on the bow-frame K, operated by the said spring-key shank V', and the spring Q', operated by the said spring T and engaging a notch on the bolt 40 O of the said bow-frame J, substantially as shown and described.

8. The bow-frame K, the hooks K' on the said bow-frame, and the key R, in combination with the bow-frame J, the shaft P' on the 45 said bow-frame, the pinion P, attached to the said shaft, the sliding bolts O and O', provided with rack-teeth O², which engage the said pinion P, and the hooks O⁴, attached to the said bow-frame J and engaging the hooks K' of the 50 bow-frame K, substantially as shown and described.

In testimony whereof I have signed my name to this specification in the presence of two subscribing witnesses.

CARL FRIEDRICH TELLER.
